DESIGN FOR A COMBINATION NEWEL POST AND SCORE TABLE FOR BOWLING ALLEYS

Alfred Reiss, Newton, Mass.

Application April 9, 1941, Serial No. 100,262

Term of patent 7 years

To all whom it may concern:

Be it known that I, Alfred Reiss, a citizen of the United States, residing at Newton, in the county of Middlesex and State of Massachusetts, have invented a new, original, and ornamental Design for Combination Newel Posts and Score Tables for Bowling Alleys, of which the following is a specification, reference being had to the accompanying drawing, forming part thereof.

Figure 1 is a perspective view of a combination

newel post and score table for bowling alleys, showing my new design. Figure 2 is an end elevational view thereof and Figure 3 is a top plan view on a reduced scale.

I claim:

The ornamental design for a combination newel post and score table for bowling alleys, as shown.

ALFRED REISS.
